Primary Examiner — David E Allred*(74) Attorney, Agent, or Firm* — Thorpe, North & Western, LLP(57) **ABSTRACT**

A folding mesh chair includes a seat and a backrest carried between opposite frame sides. The chair has an unfolded seating position in which the seat pivots to extend from the frame sides and bottoms of front and rear legs move apart, and a folded position in which the seat pivots toward the frame sides and the front and rear legs move together. One or both of the seat and the backrest have a continuous sheet of flexible and elastic mesh or patterned open texture plastic held across and substantially covering an opening in an all-plastic hoop fixed between the frame sides.

BACKGROUND

1. Field of the Invention

The present invention relates generally to folding chairs. More particularly, the present invention relates to a mesh folding chair.

2. Related Art

Folding chairs are often used in situations in which it is desirable or necessary to provide varying numbers and/or varying layouts of chairs, such as during conventions, seminars, conferences, etc. In addition, folding chairs are often used in multipurpose areas in which patron seating is required for some functions, but a large open space is required for other functions necessitating storage of the chairs. For example, some organizations have buildings with a multipurpose room which may be used for banquets, seminars, conventions, etc., with chairs set up, or for a dance, sporting event, etc., with the folding chairs removed. Furthermore, folding chairs are often used domestically/residentially to accommodate larger dinner-parties or the like.

It is desirable that the folding chairs be capable of being folded and stacked for storage so that the chairs take up less room when they are not required. It will be appreciated that some situations or events will require thousands of folding chairs, all of which may need to be folded and stored at any given period. Thus, the chairs must be folded and stored such that they have a high storage density to minimize the storage space required. It will be appreciated that any extra thickness of a chair when folded becomes significant when numerous folding chairs are involved. For example, with a thousand stacked folding chairs, a folding chair which saves one extra inch in the folded position results in over 80 linear feet of saved storage space. In addition, it will be appreciated that numerous stacked chairs can be difficult to handle or store, and may separate from one another. Furthermore, it

will be appreciated that chairs can be unsymmetrical so that stacking several chairs together results in a non-linear stack which can lead to separation.

One disadvantage with many prior art folding chairs is the bulk or thickness of the chair in the folded position. Many typical folding chairs still remain several inches thick in the folded position, and thus are less dense when stored. For example, many typical folding chairs have seats which fold adjacent to or abut the legs, such that the thickness of the chairs in the folded position comprises the thickness of the legs and the seat.

In addition, it is desirable that the folding chairs be easily storable or stackable, and be stable when stored/stacked. Many typical prior art folding chairs are stored merely by leaning one chair against a wall and subsequent chairs in a series against the first chair. It will be appreciated that a plurality of folding chairs stacked against a wall has a potential domino effect, with all of the chairs subject to being knocked over. Other prior art folding chairs have complicated and expensive hanging rack systems. For example, a wheeled cart might have a plurality of support arms from which a plurality of folding chairs is suspended. One disadvantage of these types of systems is that chairs on the end of the hangers tend to fall off the rack, and the wheeled racks are difficult to move and maneuver.

It also is desirable that the chairs be comfortable. Typical prior art folding chairs have rigid metal seats and seat backs which can be hard and uncomfortable. One disadvantage of many prior art folding chairs is that the chairs either fold well and are uncomfortable, or are comfortable but are awkward in folding. Thus, there tends to be a trade off between comfort and foldability. Some chairs provide a cushion. But these chairs still utilize the rigid metal seat bottoms and seat backs, and the cushions tend to make the chairs even thicker when folded. For example, see U.S. Pat. Nos. 2,877,829 and D357,365.

Other types of chairs, such as office chairs, have been design for greater comfort and aesthetic appearance, but which do not fold or stack. For example, see U.S. Pat. Nos. 6,125,521 and 7,249,802.

SUMMARY OF THE INVENTION

It has been recognized that it would be advantageous to develop a folding chair with greater comfort while maintaining high density storage. In addition, it has been recognized that it would be advantageous to develop a chair utilizing a mesh seating surface for comfort and space saving in a folding chair. In addition, it has been recognized that it would be advantageous to develop a chair utilizing the comfort of a mesh seating surface in a folding and stacking chair. In addition, it has been recognized that it would be advantageous to develop such a folding and stacking chair with a mesh seating surface that is both economically viable and structurally sound.

The invention provides a folding chair with: a pair of front legs; a pair of backrest supports extending upward from the pair of opposite front legs; a pair of rear legs pivotally coupled to the pair of front legs and pivotal to a folded position behind the pair of front legs; a front lower cross member extending between the pair of front legs nearer a lower end of the pair of front legs; a rear lower cross member extending between the pair of rear legs nearer a lower end of the pair of rear legs; a backrest carried between the pair of backrest supports; and an all-plastic seat hoop pivotally coupled to the pair of front legs and the pair of rear legs. Exterior lateral sides of the seat hoop are coupled to interior

sides of the pair of front legs and the pair of rear legs. The all-plastic seat hoop forms the sole structural support between the pair of front legs and the pair of rear legs above the front and rear lower cross members and below the backrest. A pair of links is pivotally coupled between the pair of front legs and the pair of rear legs above the seat hoop. A continuous sheet of flexible and elastic mesh or patterned open texture plastic is held across and substantially covers an opening in the all-plastic seat hoop and borders by the all-plastic seat hoop.

In addition, the invention provides a folding chair with a pair of all-plastic hoops including an all-plastic seat hoop and an all-plastic backrest hoop with the seat hoop pivotal with respect to the backrest hoop. A pair of continuous sheets of flexible and elastic mesh or patterned open texture plastic are held across and substantially cover respective openings in both the all-plastic seat hoop and the all-plastic backrest hoop, with each of the all-plastic seat and backrest hoops bordering the respective continuous sheet around a perimeter thereof. A frame carries the pair of all-plastic hoops and has opposite frame sides coupled together by the all-plastic backrest hoop at a top thereof, the all-plastic seat hoop at a middle thereof, and lower cross members nearer a lower end thereof. The pair of all-plastic hoops provide support for both the opposite frame sides and the sheet of flexible and elastic mesh or patterned open texture plastic.

In addition, the invention provides a folding chair with a seat and a backrest carried between opposite frame sides each with a backrest support, a front leg and a rear leg, and having an unfolded seating position in which the seat pivots to extend from the frame sides and bottoms of the front and rear legs move apart, and a folded position in which the seat pivots toward the frame sides and the front and rear legs move together. One or both of the seat and the backrest have a continuous sheet of flexible and elastic mesh or patterned open texture plastic held across and substantially covering an opening in an all-plastic hoop with only lateral sides of the all-plastic hoop coupled to the frame sides.

In addition, the invention provides a folding chair with a seat and a backrest carried between opposite frame sides each with a backrest support, a front leg and a rear leg, and having an unfolded seating position in which the seat pivots to extend from the frame sides and bottoms of the front and rear legs move apart, and a folded position in which the seat pivots toward the frame sides and the front and rear legs move together. The seat has a continuous sheet of flexible and elastic mesh held taut across and substantially covering an opening in an all-plastic seat hoop. The seat hoop is pivotally coupled between the frame sides. The backrest has a continuous sheet of flexible and elastic mesh held taut across and substantially covering an opening in an all-plastic backrest hoop. The backrest hoop is fixed between the backrest supports of the frame sides.

Furthermore, the invention provides a folding chair with a seat and a backrest carried between opposite frame sides each with a backrest support, a front leg and a rear leg, and having an unfolded seating position in which the seat pivots to extend from the frame sides and bottoms of the front and rear legs move apart, and a folded position in which the seat pivots toward the frame sides and the front and rear legs move together. The seat has a continuous sheet of flexible and elastic mesh held taut across and substantially covering an opening in an all-plastic seat hoop. The seat hoop is pivotally coupled between the frame sides. The seat hoop has a rigid plastic seat-support bar laterally traversing the hoop of the seat and has an arcuate shape into which the sheet of mesh of the seat is deflectable. The backrest has a

continuous sheet of flexible and elastic mesh held taut across and substantially covering an opening in an all-plastic backrest hoop. The backrest hoop is fixed between the backrest supports of the frame sides. The all-plastic hoop of the backrest and the all-plastic hoop of the seat form the sole structural support between the frame sides above a bottom of the frame sides.

BRIEF DESCRIPTION OF THE DRAWINGS

10

Additional features and advantages of the invention will be apparent from the detailed description which follows, taken in conjunction with the accompanying drawings, which together illustrate, by way of example, features of the invention; and, wherein:

FIG. 1 is a front perspective view of a mesh folding chair in accordance with an embodiment of the present invention shown in an unfolded seating position and with mesh of the seat and backrest mostly removed for clarity;

FIG. 2 is a rear perspective view of the mesh folding chair of FIG. 1;

FIG. 3 is a side view of the mesh folding chair of FIG. 1;

FIG. 4 is a cross-sectional side view taken along line 4-4 of the mesh folding chair of FIG. 1;

FIG. 5 is a front view of the mesh folding chair of FIG. 1;

FIG. 6 is a rear view of the mesh folding chair of FIG. 1;

FIG. 7 is a bottom view of the mesh folding chair of FIG. 1;

FIG. 8 is a front view of the mesh folding chair of FIG. 1, shown in a folded position;

FIG. 9 is a side view of the mesh folding chair of FIG. 1, shown in the folded position;

FIG. 10 is a rear view of the mesh folding chair of FIG. 1, shown in a folded position;

FIG. 11 is a front perspective view of the mesh folding chair of FIG. 1, shown in a folded position;

FIG. 12 is a partial front perspective view of the mesh folding chair of FIG. 1, shown in a folded position;

FIG. 13 is a partial front cross-sectional view taken along line 13 (FIG. 7) of the mesh folding chair of FIG. 1;

FIG. 14a is a side view of a folding and stacking chair system in accordance with an embodiment of the present invention with a plurality of folding and stacking chairs of FIG. 1;

FIG. 14b is a partial side view of the folding and stacking chair system of FIG. 14a;

FIG. 14c is a partial cross-section view taken along line 14c of the folding and stacking chair system of FIG. 14a;

FIG. 14d is a partial side view of the folding and stacking chair system of FIG. 14a;

FIG. 14e is a partial cross-section view taken along line 14e of the folding and stacking chair system of FIG. 14a;

FIG. 15a is a perspective view of a foot in accordance with an embodiment of the present invention of the mesh folding chair of FIG. 1;

FIG. 15b is a partial perspective view of the mesh folding chair of FIG. 1;

FIG. 15c is a top view of the foot of FIG. 15a;

FIG. 16a is perspective view of a top stop in accordance with an embodiment of the present invention of the mesh folding chair of FIG. 1;

FIG. 16b is a side view of the top stop of FIG. 16a;

FIG. 16c is a perspective view of the top stop of FIG. 16a;

FIG. 17a is a partial perspective view of the mesh folding chair of FIG. 1;

FIG. 17b is a partial bottom cross-sectional view taken along line 17b (FIG. 5) of the mesh folding chair of FIG. 1;

FIG. 18a is a partial front view of a backrest in accordance with an embodiment of the present invention of the mesh folding chair of FIG. 1;

FIG. 18b is a partial cross-sectional view taken along line 18b of the mesh folding chair of FIG. 1;

FIG. 18c is a side view of the backrest of FIG. 18a;

FIG. 18d is a partial cross-sectional view taken along line 18d of the backrest of FIG. 18a;

FIG. 19a is a cross-sectional side view of another mesh folding chair in accordance with another embodiment of the present invention;

FIG. 19b is a side view of a seat of the mesh folding chair of FIG. 19a;

FIG. 19c is a perspective view of the seat of FIG. 19b;

FIG. 19d is a bottom view of the seat of FIG. 19b;

FIG. 19e is a top view of the seat of FIG. 19b;

FIG. 19f is a partial rear view of the mesh folding chair of FIG. 19a;

FIG. 19g is a partial cross sectional view of a backrest of the mesh folding chair of FIG. 19a;

FIG. 20a is a perspective view of a mesh folding chair in accordance with another embodiment of the present invention shown with a pivoting seat in an unfolded seating position and with mesh of the seat and backrest mostly removed for clarity; and

FIG. 20b is a perspective view of the mesh folding chair of FIG. 20a, shown with the seat in a folded position.

Reference will now be made to the exemplary embodiments illustrated, and specific language will be used herein to describe the same. It will nevertheless be understood that no limitation of the scope of the invention is thereby intended.

DETAILED DESCRIPTION OF EXAMPLE EMBODIMENT(S)

As illustrated in FIGS. 1-13, a folding chair, indicated generally at 10, with a mesh seat 14 and a mesh backrest 18 is shown in an example implementation in accordance with the invention. Such a folding chair can be utilized by institutions or residentially. The mesh seat and backrest have a stretched mesh over all-plastic frames or hoops to achieve upholstered comfort in a non-upholstered folding chair. In addition, the chair can use the all-plastic frames with mesh for the seat and the backrest supported by a metal frame and legs for a sturdy, strong, and light-weight chair. The seat and the backrest can be plastic and can attach to the frame and legs without metal brackets or the like. Furthermore, the seat can have a broadly curved front and upper edge, or waterfall edge, to resist a hard surface against a backside of a user's leg. Furthermore, the final shape of mesh back provides lumbar support.

The chair 10 can include a frame with opposite frame sides 22a and 22b that carry the seat and backrest therebetween. The frame sides can each include an elongated member defining a front leg 26a and 26b with a lower portion thereof, and a backrest support 30a and 30b with an upper portion thereof. Thus, the backrest support 30a and 30b is essentially an extension of the front leg 26 and 26b. In addition, the opposite side frames can each include a rear leg 34a and 34b. The frame sides 22a and 22b can be coupled together by the seat 14 and backrest 18, and by front and rear lower cross members 38 and 40 that extend between the front and rear legs respectively nearer a lower end of the legs. The front and rear legs are pivotally or movably

coupled together, and pivot or move with respect to one another. The front and rear legs can be coupled together by the seat 14 and a link 44a and 44b. Thus, the seat 14 is pivotally coupled to both the front and rear legs. Similarly, the link 44a and 44b is pivotally coupled to both the front and rear legs. The front and rear legs and the backrest support can be formed of metal, such as steel or aluminum, and can be tubular for lighter weight. The cross-sectional shape of the members and chair legs can be elliptical for added strength. In addition, the members can be curvilinear and can have a stretched s-shaped profile to facilitate stacking. The front and rear legs can have matching curvature so that they can nest adjacent one another. The chair 10 can have an unfolded seating position, as shown in FIGS. 1-7; and a folded position or a folded and stack position, as shown in FIGS. 8-11. In the unfolded seating position, the seat 14 pivots to extend from the frame sides 22a and 22b and bottoms of the front and rear legs move apart so that the chair rests on a support surface and a user can sit on the seat. In the folded position, the seat 14 pivots toward the frame sides 22a and 22b and the front and rear legs move together so that the chair can be stored in less space.

The seat 14 and the backrest 18 can each have a continuous sheet of flexible and elastic mesh (represented by 44 in FIG. 1) held taut across and substantially cover the seat and backrest. The terms "mesh" and "sheet of mesh" are used interchangeably herein to refer to a mesh material that is a continuous sheet in that it is essentially consistent in its composition of strands and intervening openings (although it may have a pattern therein) and essentially covers the entirety of the seat and/or backrest (as opposed to individual strands or discrete straps with larger openings therebetween); and that is flexible and elastic in that it readily deflects under the weight of a user and returns to its previous position after unloading (as opposed to an embossed metal or rigid screen). A space can separate the seat and the backrest, and can define a gap between the mesh of the seat and the mesh of the backrest. The space can be sized to receive the seat therein in the folded position, as shown in FIG. 8. The mesh material can include a polypropylene mesh fabric or the like. The mesh can be a woven mesh or a knitted mesh. The mesh material can include 70% elastomer monofilament with a 55 durometer and 30% polyester yarn. The elastomeric monofilament can be a polyester co-polymer (such as Hytrel by Dupont). The interwoven monofilaments can also be bonded together to resist unraveling, for example by using a coextruded monofilament with an outer layer having a lower melting point that melts in an oven to bond to adjacent monofilaments. Openings can be formed through the mesh between the strands. The openings, which may have different sizes based on the pattern of the weave, can have substantially the same size, dimension or width of the strands, or be on the same order. Other types of mesh or compositions of strands with less or more elastomer can be used. As stated above, the mesh can be woven or knitted.

Alternatively, the seat 14 and the backrest 18 can each have a continuous sheet of flexible and elastic patterned open texture plastic (represented by 46 in FIG. 1) held across and substantially cover the seat and backrest. The term "sheet of patterned open texture plastic" is used herein to refer to a plastic material that has a series or arrangement of openings across the sheet and that is continuous in that it is essentially consistent in its composition of structure and openings (although it may have a pattern therein) and essentially covers the entirety of the seat and/or backrest. In addition, the sheet of plastic is flexible and elastic in that it readily deflects under the weight of a user and returns to its

previous position after unloading (as opposed to an embossed metal or rigid screen). The sheet of plastic and the material of the sheet of plastic can be selected so that the sheet of plastic can deflect or bend. In addition, the openings can be sized and patterned to facilitate deflection or bending, and to eliminate pressure points. The openings and the material between the openings can be substantially the same size, dimension or width, or on the same order. Alternatively, an opening can be elongated and serpentine to substantially traverse a width, depth or height of seat or backrest. Again, a space can separate the seat and the backrest, and can define a gap between the sheet of plastic of the seat and the sheet of plastic of the backrest. The sheet of plastic and the all-plastic hoop can be formed together, such as by injection molding, so that the seat and backrest are manufactured as a single piece or unit. The all-plastic hoop can be distinguished from the sheet of plastic as a thicker perimeter.

In either case, the sheet of mesh or the sheet of plastic can provide the sole or only support of the user's weight. Thus, each side of the sheet of mesh or the sheet of plastic can be free or open, without other materials or fillers, such as foam or cloth.

In one aspect, only the seat can include the mesh supported by a seat frame. In another aspect, only the backrest can include the mesh supported between the backrest supports of the frame sides or a backrest frame. In another aspect, both the seat and the backrest can include the mesh. Whether one of the seat or the backrest or both include mesh can depend on the needs of the user. In addition, the sheet of mesh 44 can be held taut across and substantially cover an opening in an all-plastic hoop 48 fixed between the frame sides. For example, the seat can include an all-plastic seat hoop 52 and the backrest can include an all-plastic backrest hoop 56. The resiliency in the seat and backrest can be suited to the user's preference. In one aspect, the mesh of the seat can be stretched 4.5 to 5%, while the mesh of the backrest can be stretched 2.7 to 3.2%. Thus the backrest can have greater deflection and a softer feel because the loading on the backrest is not as great as the seat. In addition, the mesh can have variable tension along a longitudinal direction (front to back for the seat or top to bottom for the backrest) to provide for great comfort. The degree of lateral tension of the mesh of the backrest can vary along the height or elevation of the backrest to create lumbar support at a desired location. The mesh suspended between the hoops can provide greater comfort than traditional solid plastic or solid metal chairs while maintaining stackability and high density storage of folding chairs. Similarly, the mesh can have variable lateral (side-to-side) tension. The all-plastic hoops can be formed by injection molding plastic, and may be formed of, or can include, polypropylene or nylon or ABS. In one aspect, the hoops can be formed of nylon and the seat hoop 52 can weigh less than 2.5 lbs, the backrest hoop 56 can weigh less than 1.5 lbs, and together can weigh less than 4 lbs, to reduce the weight of the chair while providing sufficient strength. In another aspect, the hoops can be formed of nylon and the seat hoop can weigh less than 2 lbs, the backrest hoop can weigh less than 1 lbs, and together can weigh less than 3 lbs. In another aspect, the hoops can be formed of polypropylene and the seat hoop can weigh less than 2 lbs, the backrest hoop can weigh less than 1 lbs, and together can weigh less than 3 lbs. In another aspect, the hoops can be formed of polypropylene and the seat hoop can weigh less than 1.6 lbs, the backrest hoop can weigh less than 0.8 lbs, and together can weigh less than 2.4 lbs. The amount or weight of the plastic material of the all-plastic hoops is balanced to provide sufficient strength to the frame and the sheet of mesh or

plastic, while also reducing the weight of the chair. Such a configuration as described above can support a static load of at least 1250 lbs. In another aspect, it is believed that sufficient strength can be provided by a seat hoop with a weight as low as 1.25 lbs, a backrest hoop with a weight as low as 0.5 lbs, and a combined weight as low as 1.75. The all-plastic hoops are all-plastic in that they do not have any internal or external metal reinforcement members, although the plastic of the hoops can have fillers such as glass fibers. 5 Thus, the seat and/or backrest hoops support both the mesh and the frame, reducing the number of parts and cost of the chair. The mesh 44 can be bonded, such as chemically or adhesively, in a channel 60 (FIG. 13) in the hoops, such as by melting the material of the mesh and the hoops together, 10 or by chemical reaction, or with adhesive, or the like. Thus, the sheet of mesh can be attached to the hoop without mechanical fasteners, such as staples. (The mesh is represented by 44 in FIG. 1. Most of the mesh has been removed from the figures for clarity of the chair, seat, backrest and 15 hoops. But the mesh extends across the entire opening of the hoops 48.)

The mesh 44 of the seat 14 and backrest 18 held taut in the hoops provide the comfort of an upholstered comfort in a non-upholstered folding chair; while the hoops 48 can 20 provide the sole, or only, structural support between the frame sides above the bottom thereof, or above the front and rear lower cross members 38 and 40. As described above, the 25 hoops can provide the support for both the mesh and the frame sides of the folding chair. The all-plastic hoop 56 of the backrest provides the sole structural support between the backrest supports 30a and 30b of the frame sides 22a and 22b. Similarly, the all-plastic hoop 52 of the seat provides 30 the sole structural support between the frame sides 22a and 22b at a middle of the chair or frame sides. Together, the 35 all-plastic hoops 52 and 56 of the seat and backrest provide the sole structural support between the frame sides 22a and 22b above the bottom of the frame where the lower cross members 38 and 40 are located. The hoops can be directly 40 coupled to the frame sides, without intervening support members. The seat hoop 52 can be coupled to the frame sides, or front and rear legs, by rivets which also form pivot points. The backrest hoop 56 can couple to the backrest supports as described below. The hoops can be injection 45 molded nylon with a total weight of less than 3 lbs to provide both light weight for ease of folding and unfolding and moving the chairs, and strength to support the taut mesh across the opening and support the frame sides.

The seat 14 and/or seat hoop 52 can be sized and shaped for both comfort and structural support. The seat hoop 52 50 can have opposite, parallel, substantially straight, hoop sides 64a and 64b coupled to the frame sides. A front 68 extends between the hoop sides and the front and/or front ends of the frame sides can arc downward (with respect to the chair in the unfolded seating position), or form an arc. The sheet of mesh 44 held taut between the seat hoop forms a longitudinal convex arc (represented at 72) at the front defining a leg relief near the front of the hoop of the seat. The mesh arc 55 72 or thigh support can have a broad downward curvature to provide comfort to the user's thighs when seated. The seat hoop 52 can have a substantially square shape with rounded corners. The front 68 of the seat hoop 52 can curve forwardly out of the square shape and downwardly out of the plane of the square.

An upper surface 74, or majority thereof, of the seat is 60 oriented at an incline with respect to horizontal in the unfolded seating position, as shown in FIG. 3. The seat can be inclined between 3-7 degrees, or approximately 5

degrees, with respect to horizontal. The incline of the surface of the seat in combination with the deflection of the mesh form a more comfortable seating surface. The seat can be pivotally coupled to the frame sides by a pair of pivotal couplings including the front leg pivotally coupled to the lobe **84a** and **84b** described below and the rear leg pivotally coupled to the seat. The upper surface of the seat disposed at an incline angle of between 3-7 degrees with respect to the pair of couplings due to the lobe. The width w_s of the seat and/or seat hoop at a perimeter of the hoop is equal to or greater than 17 inches. In another aspect, the width of the seat and/or seat hoop at a perimeter of the hoop is equal to or greater than 17.5 inches. The width in combination with the mesh forms a more comfortable seating surface. The width w_c of the chair at an outside of the opposite frame sides is equal to or greater than 19 inches. Thus, the chair combines comfort with a compact size for storage.

The seat hoop **52** can also include a rigid plastic seat-support bar **76** laterally traversing the seat hoop to provide support to the seat hoop and frame sides. As a user sits on the mesh **44** of the seat **14**, the mesh pulls inwardly on the seat hoop **52**, and thus the frame sides **22a** and **22b**; which is resisted by the seat-support bar **76**. The bar has an arcuate shape that curves downwardly from the sides to the center and into which the mesh of the seat can deflect when a user sits on the seat. Each side of the bar **76** can have a pair of vertical, parallel, spaced-apart flanges **80** (FIG. 12) extending from each lateral side of the bar adjacent the seat hoop **52**. The flanges **80** can taper forming a tapered profile when viewed from the front. The taper can be thicker at the lateral sides and thinner intermediate the lateral sides. The bar **76** can be formed with the hoop **52**.

As described above, the all-plastic seat hoop **52** can be directly coupled to the frame sides **22a** and **22b** without external support members. A pair of lobes **84a** and **84b** can extend downwardly from lateral sides of the seat hoop **52** in the unfolded seating position. Each frame side **22a** and **22b**, or front and rear legs, can be pivotally coupled to a different one of the lobes **84a** and **84b** respectively. The lobes can be formed by plastic along with the chair hoop. Integral plastic spacers **88** (FIG. 13) can extend laterally beyond the chair hoop towards and abutting to the frame sides, or front and rear legs, to form a space between the frame sides and the chair hoop. The spacers can facilitate pivotal motion between the seat and the frame sides. The spacers form a bearing surface and can reduce part count by replacing traditional separate washers. The spacers can be integrally formed with the chair hoop or lobes. A bore **92** (FIG. 13) extends through the spacers in the lobes and receives a mechanical fastener, such as a rivet **96**. The rivet **96** can extend through the bore in the lobes and spacers, and through the frame sides or front and rear legs. The seat can pivot about the rivets with respect to the frame sides or front and rear legs. A recess **100** or counter bore can be formed about the bore adjacent to the frame side to facilitate insertion of the rivet during assembly.

The seat **14** and/or seat hoop **52** forms a four-bar, four-pivot linkage on each side along with the front leg **26a** and **26b**, the rear leg **34a** and **34b**, and the link **44a** and **44b**. As described above, the seat hoop **52** is all-plastic. The front and rear legs, and the links, can be non-plastic, such as steel or aluminum. Thus, the seat and/or seat hoop forms a single all-plastic link in the four-bar linkage. The front legs **26a** and **26b** and backrest supports **30a** and **30b** can be formed of at least 16 gauge steel with an oval or elongated tubular cross section. The rear legs **34a** and **34b** can be formed of at least 18 gauge steel also an oval or elongated tubular cross

section. The rivets **100** can be at least $5/16$ ". It is believed that the above described configuration provides a sufficient balance of weight savings and strength.

The backrest **18** and/or backrest hoop **56** can be sized and shaped for both comfort and structural support. The backrest hoop **56** can have opposite, parallel, substantially straight, hoop sides **104a** and **104b** coupled to the backrest supports **30a** and **30b** of the frame sides. A top **108** extends between the top ends of the hoop sides. The top can have an upward curvature. An arcuate bottom **112** extends between bottom ends of the hoop sides. The bottom arcs rearward with respect to the chair and to a greater degree than any arcing of the top in the rearward direction. The bottom of the backrest forms a deeper arc than a top of the backrest. The sheet of mesh **44** forms a lumbar support near the arcuate bottom of the hoop of the backrest. The sheet of mesh **44** stretched taut between the backrest hoop forms an upright convex arc (represented at **116**) between the top and the bottom, and a lateral concave arc (represented at **120**) between the hoop sides. The backrest hoop **56** can have a substantially square shape with rounded corners. The top **108** of the backrest hoop **56** can curve outwardly out of the square shape in the plane of the square, while the bottom **112** can curve outwardly out of the plane of the square.

The all-plastic backrest hoop **56** can be directly coupled to the backrest supports **30a** and **30b** of the frame sides **22a** and **22b**. As described above, the backrest supports of the frame sides can have a tubular configuration with an open top end. The open top ends can be oriented orthogonal to the tube and can form a flat annular opening. The backrest hoop **56** has a pair of shoulders that extend from the hoop and over the open top ends of the backrest supports to cover the openings. In addition, the backrest hoop includes a pair of opposite side fingers **124** (FIGS. **18a** and **18b**) that extend over and into the open top end to provide support between the backrest supports and to cover the open top end. The shoulders and/or fingers can have a step with a larger upper portion covering the tube, or flat annular opening, and a narrower lower portion extending into the tube and abutting the inner surface of the tube. A snap lock is formed between the backrest hoop and the backrest supports. An elongate finger **128** extends from the backrest hoop and into the open top end of the backrest supports. A hook **132** is formed on the finger and extends into a hole **136** in the backrest support. The finger is flexible and an angled surface of the hook can cause the finger to flex or bend inwardly as the finger is inserted into the open top end. The finger is resilient to snap the hook into the hole, while an orthogonal surface of the hook abuts the hole, resisting removal of the finger and hook from the open top end. Additional tabs with enlarged heads and narrow necks can be formed on the backrest hoop to extend into key holes in the backrest supports.

Referring to FIGS. **14a-17b**, the chair **10** described above can be part of a folding and stacking chair system, indicated generally at **150**, comprising a plurality of folding and stacking chairs. The chairs have an unfolded seating position, as shown in FIGS. **1-7**, in which the chairs are configured for sitting upon, and a folded and stacked position, as shown in FIGS. **14a-e**, in which the chairs are folded and stacked together. The front and rear legs can have matching profiles with the rear legs nesting in the profile of the front legs of the same chair in the folded and stacked position, as shown in FIG. **9**. In addition, adjacent stacked chairs **10** and **10'** have the front legs **26b** of one chair **10'** nesting in the profile of the rear legs **34b** of another chair **10** in the folded and stacked position, as shown in FIG. **14a**.

11

Furthermore, the backrest supports 30b and 30b' of the adjacent stacked chairs are spaced apart in the folded and stacked position. A front edge of the seat 14' of one chair 10' extends between the backrest supports 30b of an adjacent stacked chair 10 in the folded and stacked position. The seat-support bar 76' extends beyond the backrest supports of the frame sides in the folded and stacked position, and toward the adjacent stacked chair 10.

Referring to FIGS. 15a-c, the chair can have feet 160 that provide both a slip and scratch resistant surface, and a stacking aid. The feet for both the front and rear legs can be identical or universal; but with opposite orientations. Each foot 160 has a bottom surface 164 to abut a support surface in the unfolded seating position and oriented at an acute angle with respect to a bottom of the leg. In addition, each foot 160 has a channel 168 oriented transverse to the bottom surface with the channel on the front foot receiving an adjacent stacked leg in the folded and stacked position. An insert portion of the foot can be inserted into an open bottom end of the tubular front and rear legs. The insert portion can be sized to be press fit into the legs. A foot 160' on a front leg 26b' of one chair 10' abuts the rear leg 34b of the adjacent stacked chair 10, as shown in FIGS. 14a and b. Adjacent stacked chairs are laterally secured by a rear leg 34b of one chair 10 received within a channel 168 on a foot 160' of a front leg 26b' of another chair 10'.

Referring to FIGS. 16a-c, the chair can have top stops or caps 178 on tops of the rear legs 34a and 34b that provide an abutment surface between the front and rear legs, support for the front legs, and a stacking aid. The rear legs 34a and 34b of the frame sides have a tubular configuration with an open top end with a pair of top stops each disposed in a different one of the open top ends of the rear legs. The top stop 178 has opposite channels including a support channel 182 receiving the front leg 26a of the same chair in the unfolded seating position, and a stacking channel 186 receiving the front leg 26a' of an adjacent stacked chair.

The top stop or bottom of the support channel 182 has an unfolded, support abutment surface 190 (FIGS. 16c and 17b) to abut the front leg 26a of the same chair in the unfolded seating position. In addition, the top stop has an inner support fin 194 (FIGS. 17a and b) to abut an inner surface of the front leg 26a of the same chair in the unfolded seating position to resist inward bowing of the front leg. Thus, the inward force on the seat hoop from the mesh pulls on the front legs, which in turn pushes on the inner fin 194 of the rear legs. Furthermore, the top stop has an outer fin 198 (FIGS. 17a and b) forming the support channel 182 along with the inner fin 194 to receive the front leg of the same chair.

The top stop or bottom of the stacking channel 186 has a folded, stacking abutment surface 202 (FIGS. 14e and 16a) to abut the front leg 26a' of an adjacent stacked chair. In addition, the top stop has an outer stacking fin 206 (FIG. 14e) to abut to an outer surface of the front leg 26a' of the adjacent stacked chair to resist movement between adjacent stacked chairs. Furthermore, the top stop has an inner fin 210 (FIG. 14e) forming the stacking channel 186 along with the outer fin 206 to receive the front leg of the adjacent stacked chair.

The top stops can have an insert portion for insertion into the open upper end of the rear legs and forming an interference fit. In addition, the top stops can have a rivet hook 214 extending into the rear legs and around a rivet through the rear legs. The top stops can be formed of plastic. The plastic can be flexible to flex and snap around the rivet during assembly. The plastic can include a harder plastic

12

body 218 with a softer plastic 222 disposed over the body, such as on the abutment surface or fins to resist injury to pinched fingers and/or to reduce noise, as shown in FIGS. 16a and 16b.

Referring again to FIG. 14a, adjacent stacked chairs 10 and 10' are separated by a top stop 178 on a rear leg 34b of one chair 10 abutting the front leg 26b' of another chair 10' and a foot 160' on the front leg 26b' of the other chair 10' abutting the rear leg 34b of the one chair 10. Separating the front and rear legs of adjacent stacked chairs helps resist damage or marring of the surface finish of the legs and helps resist noise during stacking and unstacking. In addition, adjacent stacked chairs 10 and 10' are laterally secured by a rear leg 34b of one chair 10 received within a channel 168 on a foot 160' of a front leg 26b' of another chair 10', and the front leg 26b' of the other chair 10' received within a stacking channel 186 on a top stop 178 of the rear leg 34b of the one chair 10. The channels or fins thereof help maintain the chairs in the stack and resist relative movement of the chairs with respect to one another. Thus, the top stop and foot of adjacent stacked chairs work together.

When several chairs are stacked and horizontally oriented, a greater portion of the weight or mass of the chairs is located towards the bottom of the chair (or to a lateral side when stacked). This weight keeps the bottom portion of halves of the chairs together when stacked, and keeps the upper portion or halves of the chairs separated from one another, so that the chairs maintain an aligned vertical stack.

The aspects of the chair described above help provide an improved stacking chair; with decreased weight while retaining strength and comfort; while maintaining an affordable and manufacturable chair. The curvilinear profile of the frame and chair legs in the folded configuration and the alignment channels of the top stops and the feet combine to provide a stable and stackable chair. In addition, the mesh stretched between plastic hoops provides comfort and reduces weight while maintaining strength and affordability.

As described above, the seat and the backrest, or the hoops thereof, can be injection molded. The mesh can be secured between the mating hoops and the hoops attached. The seat can be pivotally coupled to the elongated members and rear chair legs, such as with rivets. The backrest can be slid into engagement with the elongated members, and self-locking by the finger.

Referring to FIGS. 19a-f, another chair 10b is shown which is similar in many respects to that described above, and which description is herein incorporated by reference. In addition, the seat 14b has a mesh material 44 stretched between a pair of mating annular hoops, including a bottom (outer) hoop 300 and a top (inner) hoop 304. The hoops 300 and 304 can match or mate together to sandwich the mesh material 44 between the hoops. Similarly, the backrest 18b has a mesh 44 material stretched between a pair of mating annular hoops, including a rear (outer) hoop 308 and a forward (inner) hoop 312. The mesh can be stretched and then sandwiched and held between the hoops. For example, the mesh extends over an outer perimeter of the inner hoop and into an interface between the inner and outer hoops.

The pair of mating annular hoops of the seat can include mating annular notches. The mating notches can trap or sandwich the mesh material. The bottom hoop can include an annular notch formed around a top inner perimeter. The top hoop can be received within the annular notch. The top hoop can have an annular flange formed around a bottom inner perimeter and extending within an inner perimeter of the bottom hoop. In addition, the top hoop can have an upper surface 316 that is curved and inclined inwardly for comfort.

13

The mesh material can extend over the top or upper surface of the top hoop and between the hoops. The hoops can be attached by mechanical fasteners, such as screws or staples. In addition, the hoops can be joined by adhesive, sonic welding, etc.

The outer hoop 300 of the seat includes lateral hooks 320 (FIGS. 19c and d) extending inward with respect to the outer hoop and retaining the inner hoop 304 from pulling inward under tension placed on the sheet of mesh. The lateral hooks can have a channel therein to receive the inner hoop. The lateral hooks allow tension to be placed from the inner hoop onto the outer hoop directly without placing sheer stress on fasteners.

Alternatively, the inner hoop of either the seat or the backrest can have a projection or flange, such as an annular flange, that extends into a channel or groove of the outer hoop, such as a mating annular channel, so that force applied to the inner hoop is transferred to the outer hoop through the mating projection and channel to reduce stress on any fasteners. Alternatively, the projection can be formed on the outer hoop and the channel can be formed on the inner hoop.

Referring to FIG. 19g, the hoops 300 and 304 and/or 308 and 312 of the seat 14b and/or backrest 18b can include an integral snap lock fastening system. A plurality of forwardly projecting hooks 324 is formed on either the inner or outer hoop, such as an interior projecting flange formed on the outer hoop 300 and/or 308. The hooks are received in a plurality of notches or apertures 328 formed in the other hoop, such as inner hoop 304 and/or 312. The notches can be recessed in the inner hoop. The plurality of hooks in the plurality of notches retains the inner hoop on the outer hoop. The hooks can include opposite hook pairs facing in opposite directions. The hoop and the plurality of hooks can be formed as a single, integrally formed, plastic unit. Alternatively, the hoops can be attached by mechanical fasteners, such as screws or staples.

The outer hoop 300 of the seat 14b includes an interior projecting flange 332. A plurality of cut-outs 336 can be formed in the flange to reduce weight.

Referring to FIGS. 20a and 20b, another mesh folding chair 10c in accordance with the present invention is shown which is similar in many respects to that described above, and which description is herein incorporated by reference. The chair 10c can have a seat 14c that pivots with respect to frame sides and back rest when the remainder of the chair is still in the unfolded position. Such a chair can be ganged together with other chairs to form a row of chairs for use in arenas and the like with the seats pivoted to a folded position to increase a passage between adjacent rows. The rear of the seat can be pivotally coupled to the rear legs as described above, but not to the front legs as described above. Instead,

14

a pseudo-seat link 400 can be pivotally coupled between the front and rear legs, in place of the seat. Thus, the pseudo-seat link can take the place of the seat in the four-bar linkage and fold with the chair. The chair can rest on a tab 404 extending from the link to support the seat when the seat is in the unfolded position. The flange holds the weight of the user when the user sits on the seat. The link and flange can be formed of metal.

Although one frame or folding configuration has been described above and shown in the drawings, it will be appreciated that other frame and folding configurations can be used with the mesh seat and/or mesh backrest of the present invention.

While the forgoing examples are illustrative of the principles of the present invention in one or more particular applications, it will be apparent to those of ordinary skill in the art that numerous modifications in form, usage and details of implementation can be made without the exercise of inventive faculty, and without departing from the principles and concepts of the invention. Accordingly, it is not intended that the invention be limited, except as by the claims set forth below.

The invention claimed is:

1. A folding chair, comprising:

a) a seat and a backrest carried between opposite frame sides each with a backrest support, a front leg and a rear leg, and having an unfolded seating position in which the seat pivots to extend from the frame sides and bottoms of the front and rear legs move apart, and a folded position in which the seat pivots toward the frame sides and the front and rear legs move together; and

b) one or both of the seat and the backrest having a continuous sheet of flexible and elastic patterned open texture plastic held taut across and substantially covering an opening in an all-plastic hoop fixed between the frame sides, wherein

the sheet of patterned open texture plastic is formed together with the all-plastic hoop as a single unit by injection molding.

2. A chair in accordance with claim 1, wherein the sheet of patterned open texture plastic is distinguished from the all-plastic hoop by thickness, where the all-plastic hoop has a greater thickness than the sheet of patterned open texture plastic and forms a perimeter around the sheet of patterned open texture plastic.

3. A chair in accordance with claim 1, wherein the sheet of patterned open texture plastic is attached to the all-plastic hoop without mechanical fasteners.
